UNITED STATES PATENT OFFICE.

AUGUSTE CHANARD, OF RUEIL, FRANCE.

INCENDIARY MASS.

1,325,618.

Specification of Letters Patent. Patented Dec. 23, 1919.

Application filed July 15, 1918. Serial No. 245,003.

To all whom it may concern:

Be it known that I, AUGUSTE CHANARD, of 16 Avenue de Paris à Rueil, Seine and Oise, France, chemist, have invented Incendiary Masses, of which the following is a full, clear, and exact description.

Attempts have already been made to utilize pitches, tars and resins, for the purpose of forming incendiary masses. These 10 bodies, however, are not easily inflammable. Consequently the creation of fires with these materials is laborious and uncertain. Furthermore the fires are not very intense.

The incendiary mass forming the subject-matter of the present invention consists essentially:

A. Of a substance which, although not easily inflammable at normal temperatures, is combustible and, preferably, adapted to 20 burn with a long and steady flame when ignited by contact with a medium at a high temperature. As examples of substances of this kind I may mention tars, pitches, coniferous or other resins, either natural or 25 artificial, deprived of their natural oil content or not; stearic acid, naphthols, naphtholin, vaseline, or other combustible derivatives of natural or artificial greases or tars, any of these substances being employed alone 30 or mixed with others.

B. To the selected mass is then added petrol, oil, alcohol, ether or any highly inflammable solvents, appropriate fuels, liquid or solid, singly or mixed together, in such 35 a way as to obtain either hot or cold a more or less thick paste.

C. In this paste are then embedded, either 40 hot or cold, any substances natural or artificial, mineral or organic, liquid or solid, which are particularly good supporters of combustion, such as: nitrates, chlorates, peroxid, nitrated cellulose, nitrated glycerin, etc., alone, mixed together or combined.

It will therefore be understood that the 45 mass obtained will be to the desired extent inflammable and intensely combustible.

The following is one method of putting the invention into practice:

100 parts of resin and 33 parts of turpentine oil for instance are taken and the 50 whole placed under a gentle fire.

When all is dissolved 50 parts of celluloid or nitrated cellulose, divided into small

pieces, are introduced into this mass and distributed as regularly as possible by stirring. 55

The incendiary mass is then ready: the least flame will set it alight with ease and certainty, and the fire will spready briskly and will be violently intense, giving abundant long and massive flames, thanks to the double distillation of the components resins and celluloid. 60

The examples and proportions indicated above are only given by way of indication 65 and not limitation. Other proportions and other methods of preparation may be devised without going outside the principle of the invention.

The incendiary mass obtained is poured 70 into any receptacles of any shapes and dimensions and of any materials; wood, textiles, metals, etc.

The inflammability of this incendiary mass, which is already considerable, may be 75 still further increased by using the ignition device illustrated in the accompanying drawings, in which:

Figure 1 is a sectional elevation of the device embedded in the incendiary mass, and 80

Fig. 2 is an elevation, partly in section of the device in a different position.

Referring to Fig. 1, *a* designates the incendiary mass in which there is embedded a hollow cylinder *b* of combustible material, 85 for example celluloid. The cylinder *b* which may measure from 15 to 50 millimeters in diameter according to the size of the mass, is closed at both ends, and filled with a highly inflammable material such as chips 90 of celluloid or cotton soaked in petrol. A suitable igniting means such as a Bickford fuse *d* extends into the interior of the cylinder *b*.

This ignition relay allows of the sudden 95 ignition of the whole of the incendiary mass, which may comprise one or more vent holes *e* for the purpose of facilitating the sudden ignition of the whole of the mass.

In the modification shown in Fig. 2 the 100 cylinder *b* is introduced into the mass through, and arranged lengthwise in, the vent holes *e*.

The incendiary mass forming the subject-matter of the present invention is intended 105 to be used for all purposes, industrial or

military, whether it be set in operation directly or carried or sent by any means or suitable projectiles.

It is likewise intended for the charging 5 of the shells called "tracers" or "incendiary shells."

Claims:

1. An incendiary mass comprising resin, a solvent for the latter and nitrated cellulose divided into small pieces and distributed in the mass.

2. An incendiary mass comprising resin, a solvent for the latter and celluloid divided into small pieces and distributed in 15 the mass.

3. An incendiary mass comprising a combustible substance, a celluloid tube, closed at both ends and introduced in the mass, a very easily inflammable material contained in 20 this tube, and means for igniting the said material.

4. An incendiary mass comprising a combustible substance, a body for supporting the combustion, mixed with the said substance, 25 a celluloid tube, closed at both ends and introduced in the mass, a very easily inflammable material contained in this tube and means for igniting the said material.

5. An incendiary mass comprising a combustible substance, a body for supporting the combustion, mixed with the said substance, a celluloid tube, closed at both ends and introduced in the mass, chips of celluloid contained in the said tube, and an ignition device opening in the middle of the 30 chips of celluloid.

6. An incendiary mass comprising resin, a solvent for the latter, and celluloid divided into small pieces in the mass; a celluloid tube, closed at both ends and introduced in the mass, chips of celluloid contained in the said tube, and an ignition device opening in the middle of the chips of celluloid.

7. An incendiary mass comprising a combustible substance, an ignition relay comprising a tube of preëminently combustible material, closed at both ends and introduced in the mass, a very easily inflammable material contained in the said tube, means for igniting the said material, vent holes passing 45 through the incendiary mass and putting this ignition relay into communication with the atmosphere.

8. An incendiary mass comprising a combustible substance, a solvent for the latter, a body for supporting the combustion, an ignition relay comprising a tube of preëminently inflammable material, closed at both ends and introduced in the mass, a very easily inflammable material contained in the said 50 tube, means for igniting the said material, vent holes passing through the incendiary mass and putting the said ignition relay into direct communication with the atmosphere.

The foregoing specification of my "incendiary mass," signed by me this twenty-sixth day of June, 1918.

AUGUSTE CHANARD.
